UNITED STATES PATENT OFFICE

MORGAN B. SCHILLER, OF PITTSBURGH, PENNSYLVANIA, ASSIGNOR TO AMERICAN TUBULAR ELEVATOR COMPANY, OF PITTSBURGH, PENNSYLVANIA; A CORPORATION OF PENNSYLVANIA

SECTIONAL TUBULAR TOWER

Application filed July 25, 1929. Serial No. 380,818.

This invention is for a sectional tubular elevator tower of the general type disclosed in patent to Schiller and Haller No. 1,676,161 of July 3, 1928, and is for a joint for connecting the leg sections of such a tower.

According to the present invention there is provided a knock-down elevator tower construction which can be conveniently used and more satisfactorily used under certain conditions than elevator towers as heretofore constructed and as shown, for instance, in United States patent to Schiller and Haller No. 1,676,161 and B. W. Connely Patent No. 1,641,801. According to the construction shown in the Connely patent the two bolts to which the system of bracing on two sides of the tower are connected are in the same horizontal plane, so that the length of the bolts used is limited to the length of

bolt which can be inserted in the coupling sleeve. Bolts passing diametrically through the joint cannot be used. In the construction shown in the Schiller and Haller patent bolts of any desired length can be used because the bolts are in different planes, but the arrangement imposes certain limitations in the erection of the towers due to the fact that one section of a tower cannot be completed until the leg members of the next

section above it are put in place. In the present invention there is provided an arrangement wherein through-bolts of any suitable length may be employed, the bolts being in different horizontal planes, but the arrangement is such that the leg portions of the next adjacent section do not have to be put in place until a given section is completed. In other words, the arrangement is such that a leg section can be inserted in

the joint after the bolts for the diagonal and horizontal bracing have been put into place and the diagonal and horizontal braces secured thereto. This arrangement considerably facilitates the erection of towers of this nature and eliminates considerable risk in the erection thereof.

The invention may be readily understood by reference to the accompanying drawings which illustrate a preferred embodiment of my invention and in which

Figure 1 is a vertical section through the joint without the diagonal and horizontal girts;

Figure 2 is a perspective view showing the end portion of one of the leg sections; 55

Figure 3 is a view similar to Figure 1 showing all of the girts and braces in place;

Figure 4 is a horizontal section in the plane of line IV—IV of Figure 3; and

Figure 5 is a view similar to Figure 1 60 showing a slightly modified form of the invention.

In the drawings, 2 designates the upper end of a lower leg section in a tubular elevator tower of the type disclosed in the said Schiller and Haller patent. Resting on the upper end of the lower leg section 2 is the lower end of an upper leg section 3. The joint between the two leg sections is surrounded by a sleeve 4. The leg section 2 70 and the sleeve 4 have registering holes 5 therein, and passing diametrically through the registering holes 5 is a bolt 6. The bolt 6 is in a plane below the plane of the meeting ends of the two leg sections. It will be noted that the bolt 6 passes diametrically through the sleeve, and through the tube 2. 75

In the upper end of the leg section 2 at diametrically opposite points are semi-circular notches or recesses 8. The upper leg 80 section 3 is provided with registering notches or recesses 9. The sleeve 4 is provided with diametrically opposite holes 10 which register with the openings formed by the registering notches 8 and 9 in the abutting leg sections.

A bolt 11 at right angles to the bolt 6 passes through the holes 10. The notches 8 and 9 accommodate the bolt 10.

Carried on the bolt 6 is a horizontal girt 90 12, and diagonal girts 13 and 14 forming the bracing structure for one side of the tower. Secured to the bolt 11 is a horizontal girt 15 and diagonal girts 16 and 17 95 forming the bracing structure for the other side of the tower, the girts 15, 16 and 17 being in planes at right angles to the girts 12, 13 and 14.

In the erecting of the tower structure, the sleeve 4 may be applied to the upper part 100

of the leg section 2, and the bolt 6 passed through the holes 5. The horizontal girt 12 can then be applied to the projecting end of the bolt 6, and the diagonal girts 13 and 14 can be fastened thereto after which the nut 7 can be applied. At the same time the bolt 11, which extends through the joint at right angles to the bolt 6, can be put in place. It is not necessary that the upper leg section 3 be in place when the bolt 11 is put through the joint, and just as soon as the bolt 11 is put through, the horizontal girt 15 and the diagonal girts 16 and 17 can be attached to the projecting end thereof. It is therefore unnecessary to start the erection of the next section of the tower until the next preceding lower one has been completed except that the girts 14 and 17 form a part of the next section.

When the next section is erected, the leg section 3 is first inserted in the upper part of the sleeve 4, and the notch 9 is fitted over the bolt 11. This lines up the upper leg section with respect to the lower leg section, holding the upper leg section against rotation with respect to the lower one. After the upper leg section has been inserted in the sleeve, the nut 11a on the bolt 11 may be tightened to compress the sleeve against the end of the leg section 3 and thereby make tight joint. The nut 7 on the bolt 6 can also be tightened to an extent sufficient to hold the sleeve tight on the lower leg section. The fit between the leg and sleeve is naturally a close one so that when the nut on the through bolt is tightened up, the sleeve is slightly sprung, and the inside wall of the sleeve is clamped tightly against the outside wall of the leg, thus taking up any slight play in the joint and making a stiffer joint than is the case when such clamping action is not present.

In the construction herein described, the bolt 6 is in a plane below the bolt 11, so that the bracing on one side of the tower is secured to the leg sections in a plane below the similar bracing on the other side of the tower at right angles thereto. This is of particular importance, where a group of towers are used together to support a scaffolding, and the individual towers of the group are connected by horizontal girts. At the same time the bolts 6 and 11 can both be set in place and before the legs of the next upper section are inserted in the joint. By reason of the fact that the notches 8 and 9 need accommodate only the shank of the bolt, and not the head of the bolt, only a relatively small portion of the abutting ends of the tube sections are cut away. The bolts 6 and 11 pass entirely through the joint. They can therefore be of any length necessary. Double bracing can therefore be conveniently used where it is necessary, and extra girts for connecting adjacent towers

can be used, the length of the bolts imposing no limitation in this respect.

Where it is desirable, an additional bolt 18 may be provided, this additional bolt merely connecting the sleeve 4 with the lower portion of the upper leg section 3, thereby providing a joint which will not come apart when the load on the tower leg is in tension instead of in compression, as is sometimes the case where a boom is used on the tower.

In the arrangement shown in Figure 5 the lower leg section 2' is not notched, and the bolt 11' is received entirely in a notch 9' in the lower end of the upper leg section 3'. By notching only one of the leg sections, the manufacturing operations are slightly reduced, but the structure retains the advantages of the construction shown in Figure 1.

In either form of tower, the notch in the upper leg section, cooperating with the bolt 9 or 9' will prevent the upper leg section from turning with respect to the sleeve, which sleeve is bolted to the lower leg section. Thus the invention, while facilitating the erection and dismantling of the tower, provides a structure wherein proper alignment and positioning of the respective leg sections is secured.

I claim as my invention:

1. In a sectional tubular tower, aligned leg sections, a sleeve surrounding the adjacent ends of the sections, a bolt passing through the sleeve and one of the leg sections to which a system of bracing for one side of the tower is secured, and a bolt passing through the sleeve between the abutting ends of the leg sections at right angles to the first bolt to which a system of bracing for another side of the tower is fastened.

2. In a sectional tubular tower, upper and lower leg sections, a sleeve enveloping the upper end of the lower leg section and the lower end of the upper leg section, a bolt passing diametrically through the sleeve and the upper end of the lower leg section and connecting the two, a second bolt above the first at right angles thereto and passing diametrically through the sleeve, a system of braces for one side of the tower fastened to one bolt, and a system of braces for another side of the tower connected to the other bolt, said upper leg section and said bolts being so disposed that the upper leg section is insertable in the sleeve and removable therefrom when both of the said bolts are in place.

3. In a sectional tubular tower, upper and lower leg sections, a sleeve enveloping the upper end of the lower leg section and the lower end of the upper leg section, a bolt passing diametrically through the sleeve and the upper end of the lower leg section and connecting the two, a second

bolt above the first at right angles thereto and passing diametrically through the sleeve, a system of braces for one side of the tower fastened to one bolt, a system of 5 braces for another side of the tower connected to the other bolt, said upper leg section being notched at its lower end to straddle the second bolt whereby it is removable and insertible in the sleeve while the bolts 10 are in place, and a third bolt above the first two passing through the sleeve and through holes in the upper leg section for connecting the upper leg section and the sleeve and thereby holding the leg against 15 removal.

4. In a sectional tubular tower, upper and lower leg sections, a sleeve enveloping the upper end of the lower leg section and the lower end of the upper leg section, a bolt 20 passing diametrically through the sleeve and the upper end of the lower leg section and connecting the two, a second bolt above the first at right angles thereto and passing diametrically through the sleeve, a system of 25 braces for one side of the tower fastened to one bolt, and a system of braces for another side of the tower connected to the other bolt, said upper leg section being removable and insertible in the sleeve while the bolts are 30 in place, the lower end of the upper leg section being recessed to straddle the second bolt. 95

5. In a sectional tubular tower, upper and lower leg sections, a sleeve enveloping the upper end of the lower leg section and the lower end of the upper leg section, a bolt 35 passing diametrically through the sleeve and the upper end of the lower leg section and connecting the two, a second bolt above the first at right angles thereto and passing diametrically through the sleeve, a system of 40 braces for one side of the tower fastened to one bolt, and a system of braces for another side of the tower connected to the other bolt, said upper leg section being removable and insertible in the sleeve while the bolts are in place, at least one of the adjoining leg sections being recessed to straddle the second bolt. 100

6. In a sectional tubular tower, upper and lower leg sections, a sleeve enveloping the upper end of the lower leg section and the lower end of the upper leg section, a bolt 45 passing diametrically through the sleeve and the upper end of the lower leg section and connecting the two, a second bolt above the first at right angles thereto and passing diametrically through the sleeve, a system of braces for one side of the tower fastened to one bolt, and a system of braces for another side of the tower connected to the other bolt, said upper leg section being removable and insertible in the sleeve while the bolts are in place, the second bolt 50 passing between the ends of the leg sections, the 105

upper end of the lower leg section and the lower end of the upper leg section having registered notches therein providing clearance for the second bolt between the ends of the two leg sections. 70

7. In a knock-down sectional tubular tower, a lower leg section, an upper leg section, a sleeve surrounding the adjoining portions of the two leg sections, two bolts at different elevations and at right angles to each other passing through the sleeve, a system of bracing at one side of the tower joined to one bolt, a system of bracing on another side of the tower joined to the other bolt, one of said bolts serving to join the lower leg section and the sleeve, said upper leg section and said bolts being so disposed that the upper leg section is insertible in the sleeve after both bolts are in place. 75

In testimony whereof I have hereunto 80 set my hand.
